US0D1073399S

(12) **United States Design Patent** (10) **Patent No.:** **US D1,073,399 S**
(45) **Date of Patent:** **** May 6, 2025**

(54) **TURNTABLE**

(71) Applicant: **Zhengmei Zhou**, Puning (CN)

(72) Inventor: **Zhengmei Zhou**, Puning (CN)

(**) Term: **15 Years**

(21) Appl. No.: **29/968,579**

(22) Filed: **Oct. 17, 2024**

(51) **LOC (15) Cl.** **07-01**

(52) **U.S. Cl.**
USPC **D7/501**

(57) **CLAIM**

The ornamental design for a turntable, as shown and described.

DESCRIPTION

FIG. 1 is a front perspective view of a turntable, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the Turntable in a disassembled state thereof; and,

FIG. 10 is a rear perspective view showing the Turntable in a disassembled state thereof.

The broken lines in the drawings illustrate the portions of the turntable, which form no part of the claimed design.

1 Claim, 10 Drawing Sheets
